DESIGN FOR AN ASHTRAY

Franz Lang, Astoria, Long Island, N. Y.

Application October 24, 1938, Serial No. 80,652

Term of patent 7 years

To all whom it may concern:

Be it known that Franz Lang, a citizen of the United States of America, residing at Astoria, Long Island, in the county of Queens and State of New York, has invented a new, original, and ornamental Design for an Ashtray, of which the following is a specification, reference being had to the accompanying drawing, forming part thereof.

I claim:

The ornamental design for an ashtray, as shown.

FRANZ LANG.
